ATTORNEY

UNITED STATES PATENT OFFICE

150,433

DESIGN FOR A BICYCLE SIDECAR

Herbert H. Lockman, Muskegon, Mich.

Application April 21, 1947, Serial No. 138,508

Term of patent 7 years

(Cl. D90—1)

To all whom it may concern:

Be it known that I, Herbert H. Lockman, a citizen of the United States, residing at Muskegon, in the county of Muskegon and State of Michigan, have invented a new, original, and ornamental Design for Bicycle Sidecar, of which the following is a specification, reference being had to the accompanying drawing, forming part thereof.

Fig. 1 is a perspective view of a bicycle sidecar showing my new design.

Fig. 2 is an elevational view of the same and

Fig. 3 is a plan view of the same.

I claim:

The ornamental design for a bicycle sidecar, substantially as shown.

HERBERT H. LOCKMAN.
